(57) **CLAIM**

The ornamental design for a security alarm bar, as shown and described.

DESCRIPTION

FIG. 1 is a front elevational view of a security alarm bar showing my new design;

FIG. 2 is a rear elevational view thereof;

FIG. 3 is a left side elevational view thereof; and

FIG. 4 is a right side elevational view thereof.

FIG. 5 is a top plan view thereof;

FIG. 6 is a bottom plan view thereof; and,

FIG. 7 is a right side elevational view showing the design in an alternate position thereof.

In the drawings, the break lines indicate that the security alarm bar has no particular length.
